IGNITION COIL

Marion Mallory, Detroit, Mich., assignor to Mallory Research Company, Toledo, Ohio, a corporation of Delaware

Application August 5, 1933, Serial No. 683,736

9 Claims. (Cl. 175—361)

The object of this invention is to provide an improved ignition coil, which can be assembled without the use of a sealing compound.

This problem is briefly:—

5 To place the windings of the coil around the core into a bakelite case and to hold the core from axial and radial movements without the use of the usual sealing compound.

The solution is briefly:—

10 To provide a slot in the roof of the case and a similar slot in the inside of the cover. Inside of these slots, rest the two ends of the laminated core of the coil, which are flexed or bent at right angles to the plane of the laminations. When the cover is pressed into place, the coil is thus securely held by the laminations, which yield under pressure just far enough to insure that the coil is held securely against displacement in any direction by the inertia shocks to which an automobile is subjected. The coil thus floats by means of the elastic suspension exerted by the laminated core.

15 The minor problem is to provide means for clamping the coil to the support in the car without providing a complete electrical circuit, which would choke the coil.

20 The solution here is to break the electrical circuit without weakening the mechanical connection.

The third problem, of course, is to give the best 25 possible coil for the least possible money. This problem, of course, could never be completely solved, as the standard of performance changes as new materials become available.

In the figures:—

30 Figure 1 shows diagrammatically the location of the coil in the ignition circuit.

Figure 2 shows the coil in cross-sectional elevation on the plane 2—2 of Figure 3.

35 Figure 3 shows the coil in cross-sectional elevation on the plane 3—3 of Figure 2.

Figure 4 is a plan view of the coil, showing the supporting clamp.

In Figure 1, 9 is the circuit breaker mechanism and 10 is the battery. 11 is the primary circuit of the coil 12. The coil 12 comprises a high tension circuit 13, consisting of a large number of turns compared with a smaller number of turns in the primary circuit 11. 14 is the distributor.

40 In Figures 2 and 3, 15 is the high tension cable, which connects the distributor 14 to the coil 12.

45 16 is a rubber insulating bushing, which is clamped by means of the cap screws 17 and the nose piece 18 to the coil housing 19, which is made of insulating material such as bakelite.

50 55 The cable 15 contacts with the insulated high

tension wire 20, which is the outlet from the high tension turns 13 of the coil 12. These high tension turns are wound next to the laminated core 21 and 22. 23 and 24 are the low tension terminals of the outer low tension turns of the circuit 11 of the coil 12. Note that neither 11 nor 13 are shown in these Figures 2 and 3, as the complete coil 12 is not shown in sections. Through the center of each of the terminals 23 and 24, a hole is drilled, and, through these holes, 10 the wires pass, connecting with the low tension turns 11.

5 A cover 25 carries these low tension terminals 23 and 24, and, when clamped to the coil housing or case 19, it clamps the coil into place. In order 15 to secure this result, a slot 26 is provided in the cover 25 into which slot fit the end laminations of the core 21 and 22. In the roof of the case or housing 19, a corresponding slot 27 is provided into which also fits the laminated core 21 20 and 22. The cover 25 is held against a gasket 28 by means of the strap or ring 29, which is spun around the cover 25 while the latter is pressed against the case or housing 19.

In Figure 4, a clamp is shown comprising straps 25 31 and 32 held together by a bolt 30. A double hook 33 connects 31 and 32. To break the electrical circuit, an insulated strip 34 is provided between the hook 33 and the respective straps 31 and 32.

Assembling

The coil 12 is built up with the high tension turns 13 wrapped around the laminations of the core 21 and 22. Outside the turns 13, the low tension turns 11 are wound. The coil 12 thus made is placed so as to engage with the edges of the slot 27 inside of the roof 19, and the insulated high tension terminal 20 is threaded into the top of the case 19. The low tension terminals of the coil 12 are then threaded through the hollow terminals 23 and 24. The cover 25 is then pressed down upon the open end of the case 19, so as to compress the outwardly bent ends of the laminations 21 and 22 into the slots 26 and 27. Whilst held in this compressed condition, a ring of metal 29 is spun around the coil casing and cover after the gasket 28 has been inserted in place. The result is that the coil 12 is held on both ends elastically.

45 50 55 One advantage of this construction is that the low tension terminals are outside, and the high tension secondary turns are located inside so that the low tension terminals act as a shield to the radio waves set up by the high tension secondary

coil, which waves will interfere with radio reception.

Another advantage is that the ungrounded core 21 and 22 has no capacity effect to interfere with 5 the performance of the coil.

The third advantage results from the streamlined shape. The coil is usually held in the inverted position. Hence, water drains away from the high tension end, and it is practically 10 impossible to "short" this coil even if it is deluged with water.

What I claim is:—

1. An induction coil and case therefor for an 15 internal combustion engine ignition system, comprising a coil having the low tension turns wound outside and around the high tension turns which are wound around a laminated iron core, an open ended case of dielectric material, a cover adapted to close the open end, a high tension terminal in 20 the closed end of the case and two low tension terminals in the cover, corresponding terminals leading out of said coil, means for clamping said cover to said case so as to compress the laminations of said core, which yieldingly engage with 25 both the end of said case and said cover for the purpose described.

2. Means for supporting and protecting an ignition coil having a core with flexible end pieces and a high tension terminal at one end and two 30 low tension terminals at the other, comprising an open ended case of dielectric material enclosing said coil, said case having a conical closed end and a high tension cable therein, adapted to be connected with the high tension terminal of the 35 coil, a cover having two low tension terminals adapted to be connected with the two low tension terminals of the coil, means for clamping the cover to the case, so as to compress the yieldable ends of the core for the purpose described.

40 3. An ignition coil and case therefor, comprising an open ended case of dielectric material, a cover therefor, a laminated metal core, low and high tension turns wound around said core, electrical terminals for said turns, said laminated 45 core being bent at both ends in both directions so as to form a symmetrical yieldable support for the coil in the case, means in the closed end of the case for engaging with the bent ends of said core to prevent the coil from twisting in the case, 50 means for clamping the cover to said case so as to compress the bent ends of said core.

4. An ignition coil and case therefor, comprising an open ended case of dielectric material, a cover therefor, a core formed of rectangular metallic strips, low and high tension turns wound 55 around said cores, electrical terminals for said

turns, said laminated core being insulated from said high and low tension turns, a slot in the closed end of said case, a corresponding slot in the cover, said core being bent at both ends in both directions so as to form a symmetrical yieldable support for said coil in said case, said core being adapted to fit into said slots so as to prevent the coil from twisting in the case and breaking said terminals, means for clamping said cover to said case so as to elastically compress said laminations for the purpose described. 10

5. Means for supporting and protecting an ignition coil having a core with flexible end pieces, comprising an open ended case of dielectric material, a cover therefor, a slot in said cover, a corresponding slot in the closed end of said case, said slots being adapted to engage with and to locate the flexible ends of said core, means for clamping the case to said cover for the purpose described. 15

6. A supporting clamp for an ignition coil, comprising two metal brackets, each partially embracing said coil, a third metallic piece engaging with the ends of said brackets, an insulating strip located between the brackets and the third 20 piece for the purpose described.

7. A supporting clamp for an ignition coil, comprising two metal brackets, each partially embracing said coil, terminating in hook-shaped ends, a hook-shaped metallic piece adapted to engage with the ends of said brackets, insulation between said hook and said clamp for the purpose 25 described.

8. An ignition coil assembly comprising a case of dielectric material open at one end, a cover for the open end, a core formed of metallic strands, low and high tension turns wound about said strands, said strands having their ends bent substantially at right angles to the axis of the coil and held under elastic tension by compression 35 between said cover and the closed end of the case, said compression being in a direction parallel to the central portion of the core. 40

9. An ignition coil assembly comprising a case of dielectric material open at the bottom, a cover 45 clamped to said bottom, low and high tension windings within said case, low and high tension leads into the case, the high tension lead being through the top thereof, a nose piece secured to the top and forming therewith a stream lined contour to drain water away from the high tension lead, and a rubber bushing for the high tension lead within the nose piece and clamped between the latter and the top of the housing to exclude 50 water from the interior of the case.

MARION MALLORY.
